UNITED STATES PATENT OFFICE.

JOHN H. DEAN, OF BIRMINGHAM, ALABAMA.

FASTENING MEANS FOR BUTT-JOINT METAL CULVERTS.

1,073,965.

Specification of Letters Patent. Patented Sept. 23, 1913.

Application filed February 3, 1913. Serial No. 745,903.

To all whom it may concern:

Be it known that I, JOHN H. DEAN, a citizen of the United States, residing at Birmingham, in the county of Jefferson and State of Alabama, have invented certain new and useful Improvements in Fastening Means for Butt-Joint Metal Culverts, of which the following is a specification, reference being had therein to the accompanying drawing.

This invention relates to keys in the form of specially constructed bolts for use in fastening together and retaining in connected relation the complementary sections of my improved butt-joint nestable metal culvert which I have particularly set forth and covered in Patent No. 1,049,816, granted to me on January 7, 1913. The type of butt-joint nestable culvert herein referred to is one in which said culvert is made up of metal sections, preferably corrugated half sections, which sections have rigid metal strips or bars welded or riveted to the sides of said sections at or near their longitudinal edges, the strips or bars being so arranged with respect to said metal sections that spaces or passageways are formed at intervals between the sections and said strips for receiving the bolts. In assembling this type of culvert, the complementary sections are placed together with their longitudinal edges meeting or abutting, and the type of bolt hereinafter more particularly referred to, is provided for engaging within the passageways formed between the sections and the strips with a view to providing a means for forcing the longitudinal edges of complementary sections into true abutting relation, and furthermore for retaining said edges in such position. These bolts are also adapted to serve as a means for connecting the adjacent strips of complementary sections together, whereby said complementary sections are held and retained in proper assembled relation.

I have illustrated my invention in the accompanying drawing, in which,

Figure 1 is a side elevation of a butt-joint culvert illustrating my improved bolt in proper position for accomplishing the purpose for which it is intended; Fig. 2 is a transverse sectional view of a portion of the culvert taken on the line 2—2 of Fig. 1, and showing the longitudinal edges of the culvert in abutting relation and one form of bolt inserted in a passageway formed be-

tween the side of the culvert and the metal strips; Fig. 3 is a similar view, showing a modified form of bolt inserted within one of the passageways for holding and retaining the sections in proper position; Fig. 4 is a perspective view of the bolt illustrated in Fig. 2; Fig. 5 is a perspective view of the bolt illustrated in Fig. 3, and Fig. 6 is a sectional view taken on the line 6—6 of Fig. 2.

Referring to the drawing, it is to be noted that each section, indicated at 1, of the butt-joint culvert, is shown provided with corrugations which are arranged parallel with opposite ends thereof, and that when these sections, which are preferably half sections, are arranged in assembled position to form a completed culvert, the corrugations of upper and lower sections coincide with each other, or in other words each convex and concave corrugation of an upper section is directly in line with the convex and concave corrugations respectively of the section below it. It may be further noted that these sections are constructed without the usual outstanding flanges, but that the longitudinal edges of complementary sections are adapted to abut as indicated at 2, in the drawing, so that when said sections are connected together with their longitudinal edges meeting or abutting, the corrugated culvert, for all intents and purposes, has the appearance and strength of an integral corrugated cylinder.

As has heretofore been referred to, the culvert sections are provided at or near their longitudinal edges, with rigid metal strips or bars 3, which are secured to the convex corrugations of each section, preferably by welding or riveting the same thereto, and it will be noted that passageways, as indicated at 4, are formed between the sides of the corrugated culvert sections and the said metal strips at points intermediate the convex corrugations of said sections, and these passageways are provided for receiving my improved bolt.

In the form of key or bolt shown in Figs. 2 and 4 of the drawing, the same is constructed with an enlarged head 5, and a specially formed shank, which shank has a portion intermediate its ends, indicated at 6, which is adapted to engage the side of the culvert at a point where its longitudinal edges meet or abut, and also has portions indicated at 7—7, which engage respectively

the inner face of the adjacent metal strips 3—3. It will thus be seen that when this bolt is inserted within one of the passageways formed between the side of the culvert 5 and the adjacent strips 3—3, that the shank of said bolt engages both the side of the culvert and said metal strips, and thus serves to properly position the longitudinal meeting edges of the culvert. The passageways 10 4 are formed due to the fact that the metal strips 3 are secured to the convex corrugations of the culvert, so that said passageways are arranged at intervals between said convex corrugations, and in order to prevent the turning of the bolt within said passageways, the enlarged head 5 of said bolt is so constructed along one of its sides that it conforms to the concave corrugation of said culvert. It will thus be seen that the 15 portions 6 and 7—7 of the shank are retained in proper engagement with the side of the culvert section and the inner face of the strips 3—3 respectively, for accomplishing the purpose for which they are intended.

20 25 The shank of the bolt is of sufficient length to project below the bottom edge of the lower strip 3, and this end is screw-threaded for receiving a nut 8 which is adapted to be screwed into engagement with said lower strip and thus serve to securely fasten said bolt in position after being applied to the culvert as above set forth. Furthermore, it is to be noted that the head 5 is of sufficient size to project over and bear against the top 30 edge of the upper strip, in which event the bolt is held in proper position after being applied, and prevented from passing entirely through the passageway.

35 40 45 In Figs. 3 and 5 of the drawing, is illustrated a slightly modified form of bolt, said bolt being identical in every respect with that shown in Figs. 2 and 4 of the drawing, excepting, however, that the intermediate portion 6 of the shank is somewhat lengthened in order to provide for the forming of a horizontal portion 9 of said shank which serves together with the bottom edge of the lower strip 3, as a bearing for the nut 8.

50 55 60 In assembling this type of culvert, complementary sections are placed together as shown, and the bolts are inserted within the passageways formed between the sides of the culvert sections and the metal strips 3—3, and when so inserted serve to properly position the abutting longitudinal edges of complementary sections, and this due to the engagement of the shank of said bolt with the sides of the culvert sections and the inner face of the metal strips, as has been referred to above. These bolts not only serve to properly position said longitudinal edges of complementary sections, but also serve to retain the same in true abutting relation and furthermore act as a means for 65 tying adjacent strips 3—3 together for hold-

ing complementary sections in connected relation.

Having thus fully described my invention, what I claim and desire to secure by Letters Patent is:—

1. A bolt adapted for insertion within a passageway formed between the side of a butt-joint culvert and metal strips secured to said culvert, said bolt having a portion of its shank engaging the side of the culvert 70 and another portion thereof engaging the strips, for the purpose specified.
2. A bolt adapted for insertion within a passageway formed between the side of a butt-joint culvert and metal strips secured thereto, and adapted for holding the longitudinal meeting edges of said culvert in abutting relation, said bolt having a head 80 serving to prevent turning of the bolt within said passageway.
3. A bolt adapted for insertion within a passageway formed between the side of a butt-joint culvert and metal strips secured thereto, and adapted for holding and retaining the longitudinal meeting edges of said 85 culvert in abutting relation, said bolt having a head adapted to engage the side of the culvert and thereby prevent turning of the bolt within said passageway.
4. A bolt adapted for insertion within a passageway formed between the side of a butt-joint culvert and metal strips secured thereto, and adapted for holding and retaining the longitudinal meeting edges of said 90 culvert in abutting relation, the shank of said bolt having its end portions engaging respectively the inner faces of adjacent strips; and a portion intermediate its ends 95 for engaging the side of the culvert at a point where the longitudinal edges of said 100 culvert meet, for the purpose specified.
5. A bolt adapted for insertion within a passageway formed between the side of a butt-joint culvert and metal strips secured thereto, and adapted for holding and retaining the longitudinal meeting edges of said 110 culvert in abutting relation, said bolt comprising a head adapted for engagement with the top edge of the upper strip of adjacent metal strips, a shank so formed as to engage 115 both the side of the culvert and the inner faces of said metal strips, and a nut secured to said shank and adapted for engagement with the bottom edge of the lower strip.
6. A bolt adapted for insertion within a passageway formed between the side of a butt-joint culvert and metal strips secured thereto, and adapted for holding and retaining the longitudinal meeting edges of said 120 culvert in abutting relation, said bolt comprising a head adapted for engagement with the side of the culvert for preventing 125 the turning of said bolt within the passageway and also projecting into engagement with the top edge of the upper strip of the 130

- adjacent metal strips, a shank so formed as to engage both the side of the culvert and the inner faces of said adjacent strips, said shank having a horizontal portion at the 5 lower end thereof, and a nut having screw-threaded engagement with the shank and adapted when in proper position to bear against said horizontal portion and the bottom edge of the lower strip.
- 10 7. In combination with a corrugated metal culvert having longitudinal abutting edges and metal strips secured to the convex corrugations of said culvert along its longitudinal edges thereby forming passageways 15 between the concave corrugations and said strips, a bolt adapted for insertion within the passageways for holding and retaining the longitudinal edges of the culvert in abutting relation, said bolt having a head which is so shaped along one of its edges as to conform to the curvature of the concave corrugation and thereby prevent turning of the bolt within said passageway. 20
- In testimony whereof I have affixed my signature in presence of two witnesses.

JOHN H. DEAN.
